SEA FLOOR SEDIMENT SAMPLER

Carl J. Shipek, 3639 Pio Pico St., San Diego 6, Calif.
Filed June 22, 1962, Ser. No. 204,656

6 Claims. (Cl. 73—425.2)

(Granted under Title 35, U.S. Code (1952), sec. 266)

The invention described herein may be manufactured and used by or for the Government of the United States of America for governmental purposes without the payment of any royalties thereon or therefor.

This invention relates to devices for obtaining samples of the ocean bottom sediment layer. More particularly, it comprises a housing preferably formed by two semi-cylindrical sections, one contained within the other when armed and adapted to be rotatively closed by an interconnected spring. The spring action is triggered by an actuating pad coming in contact with the ocean floor which results in interaction of the sections to provide a cylindrical enclosure automatically housing a sediment sample at the point of ocean floor contact.

Various designs of devices have been employed for the purpose of obtaining ocean bottom samples such as the orange peel type, clam shell, grab samplers and many others. As a general rule most of these devices either fail to pick up the sample intact or carry it to the surface in a disturbed condition as a result of water currents leaking through it. The lack of sharpness of the jaws, the slow speed of operation, and finally the inadequate enclosure itself will provide a mixed-up sample from the jaw closing action or result in a washed-out diluted version caused by the water currents leaking into the enclosure as the sampler is raised by cable to the base ship on the surface.

The object of this invention is to overcome the disadvantages pointed out in the preceding paragraph.

The general purpose of the proposed sampler is to provide a device for scooping up undisturbed samples of sand, mud, clay, ooze or combination of the same from the ocean floor.

Specifically, the purpose of this sampler is to pick up benthonic organism samples in their related environment and undisturbed for analysis and study at the surface.

Another object is to provide a sampler that can be lowered by wire rope from a surface vessel to the ocean floor.

Still another object is to provide a sampler which will automatically close when reaching the sampling position on the ocean floor.

Another object of the design is to provide a device for cutting or slicing the sample segment from the ocean floor in contrast to pushing or forcing the sediment into the sampler in a rather mixed up or disturbed condition.

Another accomplishment of the particular design is its close fit or thorough enclosure for ascent to the surface.

Another purpose is to provide an efficient enclosure for sediment samples incorporating its own power source from the helical action of a coiled spring, manually armed at the start by the operator and automatically triggered at the point of operation on the ocean floor.

Another object is to provide a sampler having an enclosure portion with a solid cover to shield off currents, and provide an opening only on the lower side toward the sea floor wherein a half cylinder sampler section rotatively supported by said enclosure is snuggly fitted in said opening and adapted to automatically slice a sample from the sea floor and concurrently provide the door for closing said opening and thereby encase said sample within the enclosure.

With these and other objects in view, as will hereafter more fully appear, and which will be more particularly

2

pointed out in the appended claims, reference is now made to the following description taken in connection with the accompanying drawings in which:

FIG. 1 is a front elevation of the sea floor sediment sampler closed after a sampling operation and ready for hoisting to the base ship on the surface;

FIG. 2 is a side elevation of the same;

FIG. 3 is a perspective view from the bottom or sea floor side of the sampler, showing it open and armed for sampling; and

FIG. 4 is a fragmentary view of the inter-related components.

Briefly the sea floor sediment sampler 11 comprises a cover or housing portion 12 having an opening in its base. A sampler section or jaw 13 is rotatively supported by said cover in the base opening and is adapted upon rotation to carve out a sample of the sediment and concurrently close said base opening and encase said sample within the enclosure formed by the cover and jaw.

The preferred form of sampler illustrated herein employs two half cylinders comprising the cover 12 and sampler section or jaw 13. The half cylinder cover 12 is open along its axial plane on its bottom side toward the sea floor. The top side of the cover is a solid enclosure which diverts water currents away from the sampler as it is raised to the surface by cable 37 attached to the cover anchor ring 36.

The sampler section or jaw 13 preferred herein is a half cylinder slightly smaller than the cover 12, and is rotatively supported by said cover and is designed to fit contiguously therein when the device is armed for sampling as shown in FIG. 3. When the jaw 13 has been rotated during the operation of cutting out a sediment sample, the cutting edge 17 terminates against stops 18 FIG. 4 so that the two half cylinders are juxtaposed to form a complete cylindrical enclosure as illustrated in FIGS. 1 and 2 and automatically encase the sediment sample within said enclosure. With the contiguous fit between the cover 12 and jaw 13 the adjacent edges 15 and 17 are not only so close together that they prevent water currents from entering or passing through the cylindrical enclosure, but further the edge 17 is encased within the edge 15 of cover 12 so that said water currents are warded off by the overlap of edges 13 on 17 as the sampler is raised by cable 37 to the surface.

The power means for actuating the sampler and performing the operation of carving out a sediment sample and concurrently closing the cover opening to encase the sample, comprises a pair of coiled springs 14 interconnecting the half cylinder cover 12 and the jaw 13 and are pre-loaded under helical tension. The springs 14 are mounted on bosses 16 which in turn are fixed to the rotative jaw or sampler portion 13 and journaled in the bearing plates 41 which are fixed to cover 12.

A torsion plate 20 carrying the spring pins 23 may be adjusted circumferentially on the bosses 16 to vary the helical spring tension between the cover 12 and jaw 13. When the desired tension is obtained the nut 39 is tightened to securely fix the torsion plate 20 non-rotatively to the bosses.

The power linkage between the cover housing 12 and the sampler section 13 as a result of the helical tension on the springs, is directed through pin 22 on cover 12, to spring hook 21, spring 14 to hook 21 and pin 23, thence to torsion plate 20 and washer 35 to boss 16 which is fixed to sampler section or jaw 13. The spring tension related above is adjusted when the sampler is closed as illustrated in FIGS. 1 and 2. This is accomplished by a torsion wrench on the plate 20 when the sampler is closed FIGS. 1 and 2. In practice, it is preferred to use a cylindrical sample 8 inches in diameter and 8 inches long. When

armed, the helical spring tension is adjusted for a torsion of approximately 35 foot-pounds. After the operation, when the jaw 13 has rotated through 180 degrees and is against the stops 18, a torsion of approximately 10 foot-pounds is left on the spring 14 in order to maintain the sample sections closed during hoisting to the surface.

In order to arm the device for sampling, a wrench is attached to the hex end 24 of boss 16 FIG. 2 and rotated clockwise until the sampler section 13 is within the cover 12 as illustrated in FIG. 3 at which point the catch 26 would be swung about pivot 29 to engage the cutting edge 17 of jaw 13. Thus the sampler would be armed and its operational release controlled by keeper mechanism.

The keeper mechanism comprises a catch 26 and arm adapted to engage in the slot 27 until released by lifting the linkage 32 as a result of pressure on pad 31 from the sea floor sediment. In operation, as the sampler is lowered by cable 37, when it reaches the sea floor the pad 31 and linkage 32 are automatically lifted until the catch arm 39 is released from the slot 27 and spring 28 pulls the top of arm 39 to the right thus moving catch 26 to the left and disengaging it from edge 17 to release the sample section 13 for rotation counterclockwise.

The spring 34 across the keeper linkage operates to maintain the pad 31 in its armed position as illustrated in FIG. 3, to prevent accidental release. The safety screw 33 is provided to lock the sampler in its armed position by bearing against the horizontal arm 40 of the keeper mechanism to secure the catch arm 39 in slot 27.

What is claimed is:

1. A sea floor sediment sampler comprising a cylindrical housing assembly including a semi-cylindrical top in combination with a semi-cylindrical bottom portion, said bottom portion being rotatively mounted within said top to form a semi-cylindrical assembly open along its axial plane, axial bosses fixed to and extending outwardly of said bottom and journaled in said top so that said bottom is located in and rotatively supported by said top, coiled springs positioned on said bosses and supported under helical tension at one end to the top and the other end to the bottom through said bosses, a catch for keeping said bottom located in said top in an armed condition, and trigger means actuated by contact with the ocean floor for releasing said catch so that the semi-cylindrical bottom will rotate in relation to said top, said rotation concurrently slicing a sediment sample and forming an open-centered enclosure for encasing said sample in a relatively undisturbed condition.

2. A sea floor sediment sampler comprising a top in the shape of a half cylinder open along its axial plane, a bottom half cylinder slightly smaller than said top and open along its axial plane, said bottom being axially supported by said top and rotatively encased therein when open, spiral springs under helical tension connecting said top and bottom so that said bottom may be rotated into closed position relative to said top and form an assembled cylindrical enclosure, and trigger means actuated by sea floor contact for releasing said helical tension so that the bottom half cylinder can slice a sediment sample from the sea floor and encase it within said cylindrical enclosure for hoisting to the surface said axial support for said bottom being provided externally of the bot-

tom whereby said enclosure remains open-centered for encasing said sample in a relatively undisturbed condition.

3. A sea floor sediment sampler comprising a half cylinder top in combination with a half cylinder bottom rotatively supported axially by and snuggly within said top when armed for sampling, power means for rotating said bottom to cut out a sediment sample from the sea floor, said rotation being in relation to said top so that said top and bottom will close to form a cylindrical enclosure for encasing said sample said rotative support for said bottom being provided externally of the bottom whereby said enclosure remains open-centered for encasing said sample in a relatively undisturbed condition.

4. A sea floor sediment sampler comprising an enclosure portion provided with an opening on its lower side toward the sea floor, a half cylinder sampler section rotatively supported by said enclosure and snuggly fitting said opening, power means interconnecting said enclosure and sampler section for automatically rotating said sampler section upon contact with the sea floor so that said sampler section will automatically slice a sample from the sea floor and concurrently provide a closure for said opening and encase said sample within said closure said rotative support for said bottom being provided externally of the bottom whereby said enclosure remains open-centered for encasing said sample in a relatively undisturbed condition.

5. A sea floor sediment sampler comprising a cover portion open only on its lower side toward the sea floor, a sampler section in the form of a half cylinder open along its axial plane, said sampler section rotatively supported by said cover portion and contiguously fitting the opening therein, spiral spring means interconnecting said cover portion and sampler section for closing the sampler upon contact with the sea floor so that said sampler section will automatically slice a sample from the sea floor and concurrently provide a closure for said cover opening and encase said sample within the enclosure formed by the cover and sampler section said rotative support for said sample section being disposed externally of said sample and said spiral spring means being carried by said rotative support, whereby said center portion of said enclosure remains open for permitting said sample to be enclosed in a relatively undisturbed condition.

6. A device as described in claim 5 wherein the sample section rotative support comprises axial bosses fixed to said section and journaled in said cover portion and said spring means comprises a coiled spring under helical tension and mounted on each boss, said springs connected at one end to said cover and at the other end to the sample section through said boss.
